UNITED STATES PATENT OFFICE

WILHELM HILDEBRAND, OF GROSS-LICHTERFELDE, NEAR BERLIN,
GERMANY.

REGULATOR FOR AIR-PUMPS.

No. 821,870.

Specification of Letters Patent.

Patented May 29, 1906.

Application filed June 6, 1905. Serial No. 263,964.

To all whom it may concern:

Be it known that I, WILHELM HILDEBRAND, engineer, a German subject, residing at No. 14 Bismarckstrasse, Gross-Lichterfelde, near Berlin, German Empire, have invented new and useful Improvements in Regulators for Air-Pumps, of which the following is a specification.

My invention relates to an improved regulator for air-pumps, more particularly those which are employed for air-brakes.

The regulating-valves ordinarily employed for cutting off the pump on a certain predetermined pressure being reached in the main reservoir and for again opening the passage on the pressure sinking are generally actuated by a piston which is loaded on the one side by the pressure in the main air-reservoir and on the other side is acted upon by a spring the tension of which determines the extent of normal pressure in the reservoir.

In the case of direct-acting brakes it is, further, the general practice to connect the spring-loaded side of the piston with the main pipe so that the pressure existing in this latter during the process of braking assists the spring, and thus connects the pump on each occasion of braking. This method, however, is attended with the disadvantage that in the event of braking for a considerable time regulation of the air-pressure in the reservoir is prevented, since the braking pressure, which in certain cases may approach to that of the pressure in the reservoir, acts on the entire surface of the piston, on which, on the other side, the reservoir-pressure acts. Furthermore, this method of actuating the pump-regulator in the case of automatic brakes, and in particular with double-chamber brakes, cannot be employed, since with such the brake-pipe is always filled with air. According to my invention all these defects are overcome by connecting the regulator-piston or other movable surface such as diaphragms, with a second movable surface or piston exposed to the pressure in the pipe, which second surface is of smaller diameter than the first-named surface or main piston in order to prevent undue increase of the reservoir-pressure when the brake is applied for a considerable period of time. In this manner by slight increase of the pressure in the reservoir the action of the auxiliary surface is equalized and the main surface is enabled

to properly regulate the reservoir-pressure 55 against the pressure on the auxiliary surface.

In the accompanying drawings, Figure 1 shows a longitudinal section of a pump-regulator for automatic air-brakes, and Fig. 2 a like view of such a regulator for direct-acting 60 air-brakes.

In the regulator-casing a' a^2 a^3 a^4 two surfaces or pistons b and c are located, working, respectively, in the chambers a^2 and a^4 and connected by the rod d . In the slide-valve 65 chamber a' there is located a slide-valve e , which is actuated by fingers or lugs projecting from the piston-rod d or in the case of Fig. 2 from the piston-rod tail d' . In this manner the valve e can be moved over the 70 ports B C . In the chamber a^3 there is located the regulator-spring f , which acts upon the piston b .

The pistons b c divide the entire casing into three chambers 1, 2, and 3. The chamber 1, which also contains the valve e , is connected with the main air-reservoir by the aperture A . Of the two passages B C the former, B , conducts to the cut-off device for connecting and disconnecting the source of 80 air—viz., the pump. The other passage C conducts to the atmosphere. The chamber 2 communicates with the atmosphere and contains the spring f , which acts on the piston b . The spring-pressure opposes the 85 force exerted on the piston by the reservoir-pressure and is adapted to the normal pressure of the reservoir. The chamber 3 is connected with the brake-pipe D , so that the 90 pressure in the latter acts upon the piston c .

The manner of operation is as follows, reference being first made to the automatic-brake, Fig. 1: The tension of the spring is so adjusted as to exceed the forces exerted upon the pistons b and c by the reservoir and 95 pipe pressure so long as the normal reservoir-pressure has not been attained. The piston system is thus forced toward the left, so that the passages B and C are connected by the hollowed face of the valve e . The pump cut-off device is brought into communication with the atmosphere and the pump connected. The pressure in the main reservoir rises 100 accordingly until the main pipe-pressure acting on the differential piston b , together with the pipe-pressure acting on the piston c , overcomes the force of the spring and drives the piston system toward the right. The pass-

sage B is now uncovered, and the reservoir-air flows to the pump cut-off device, whereby the air-pump is disconnected. If air is allowed to escape from the brake-pipe, the pipe-pressure acting on the left-hand side of the piston c is also diminished. The spring f thus overcomes the counter-pressure, the pump cut-off device is brought into communication with the atmosphere, and the air-pump connected. This increases the pressure in the main air-reservoir until the main reservoir-pressure now acting on the pistons b and c equalizes the fall of pressure in the chamber 3, and thus cuts off the pump. By suitably selecting the piston areas this overpressure above the normal main air-reservoir pressure can be so adjusted that it is sufficient to release the brakes by again filling the brake-pipe and auxiliary air-reservoir, so that on release of the brakes the normal pressure in the main air-reservoir is again restored.

Referring now to the case of direct-acting air-brakes, Fig. 2, the pressure of the main air-reservoir conducted to the chamber 1 here acts on the entire surface of the piston b, and the spring f is chosen of such strength that it counterbalances this entire pressure when the pressure in the main reservoir is the normal. If now on the normal pressure in the main air-reservoir being reached the piston system, together with the valve e, is moved toward the right, the air-pump will be disconnected by flow of air into the passage B.

If compressed air is let into the brake-pipe 35 D and chamber 3 for the purpose of applying the brakes, it will in conjunction with the spring f drive the pistons b c and valve e toward the left, and so connect the air-pump. The pressure in the chamber 1 now increases 40 until the overpressure on the piston b over-

comes the pressure on the pistons c and the force of the spring f and again disconnects the pump. The ratio of the two piston areas in this case also determines the extent of the overpressure which may be produced in the main air-reservoir during the process of braking.

Instead of making use of rigid pistons other movable surfaces, such as flexible diaphragms, may be made use of.

Having thus described my invention, I claim as new—

A pump-regulator for air-brakes comprising a casing of varying diameters, two pistons therein of different diameters dividing the casing into three chambers 1, 2, 3, the chambers 1 and 2 being on opposite sides of the large piston and the chamber 3 on the rear side of the small piston, a rod connecting the pistons together, lugs on said rod, means for connecting the chamber 3 with the brake-pipe, means for connecting the chamber 1 with the main reservoir, a pipe B connecting the chamber 1 with the cut-off device of the pump, a pipe C adjacent said pipe B leading to the atmosphere, a slide-valve connected to the rod by the lugs thereon, said valve in one position connecting the pipe B with the pipe C and in its other position permitting pipe B to communicate with the chambers 1 and a spring in chamber 2 for controlling the movement of the pistons.

In witness whereof I have hereunto signed my name, this 23d day of May, 1905, in the presence of two subscribing witnesses.

WILHELM HILDEBRAND.
